UNITED STATES PATENT OFFICE

171,319

FINGER RING

Gail Bennett, Evanston, Ill.

Application September 11, 1953, Serial No. 26,768

Term of patent 14 years

(Cl. D45—10)

To all whom it may concern:

Be it known that I, Gail Bennett, a citizen of the United States and a resident of Evanston, in the county of Cook and State of Illinois, have invented a new, original, and ornamental Design for Finger Ring, of which the following is a specification, reference being had to the accompanying drawings, forming part thereof.

In the drawings:

Fig. 1 is a perspective view of a finger ring showing my new design;

Fig. 2 is a perspective view thereof taken substantially from the side; and

Fig. 3 is a perspective view thereof taken substantially from above.

The dominant features of my design resides in those portions shown in full lines.

I claim:

The ornamental design for a finger ring, substantially as shown and described.

GAIL BENNETT.
